UNITED STATES PATENT OFFICE.

SAMUEL L. BEAN, OF WASHINGTON, DISTRICT OF COLUMBIA.

BOOT-CLEANER.

SPECIFICATION forming part of Letters Patent No. 367,129, dated July 26, 1887.

Application filed April 3, 1886. Serial No. 197,661. (No model.)

To all whom it may concern:

Be it known that I, SAMUEL L. BEAN, a citizen of the United States, residing at Washington, in the District of Columbia, have invented 5 certain new and useful Improvements in Boot-Cleaners; and I do hereby declare the following to be a full, clear, and exact description of the invention, such as will enable others skilled in the art to which it appertains to make and 10 use the same.

My invention consists of a boot-cleaner, which operates by a rotary brush driven by a spring-motor, which is wound up, to put the brush in operation, by a treadle so arranged 15 that the user can step on it.

In order that my invention may be clearly understood, I have illustrated in the annexed drawings, and will proceed to describe, a practical form thereof.

20 Figure 1 represents a vertical section of my improved boot-cleaner. Fig. 2 represents a sectional plan view of the same:

The rotary brush A is combined with any known suitable spring-motor, B. The motor 25 which I prefer using consists of a winding-shaft, b, connected by a strap, c, with a treadle, C. On the winding-shaft b is mounted a spur-wheel, F, which meshes with a pinion, f, on the shaft f'. On this shaft f' is mounted a 30 spur-wheel, F', which meshes with a pinion, f', on the brush-shaft. To the shaft f' is secured the inner end of a coiled spring, B, the other end of which is secured to any suitable point on the frame of the machine. These 35 parts are mounted on a suitable box, D, through

the top of which the upper part of the brush projects. A hood, D', is placed over the brush, which directs the mud and dust into the dust-receptacle D² of the box.

A person desiring to use this boot cleaner 40 steps on treadle C to wind up the spring-motor. On taking his weight off the treadle the motor will drive the brush in the direction indicated by the arrow, so that the person may have his boots cleaned by simply holding them against 45 the brush. A comb, E, may be applied to clean the brush by combing it.

I do not confine myself to the particular organization shown in the drawings, as that, as well as details, may be much varied without 50 evading my invention.

I claim as my invention—

1. A boot-cleaner composed of a rotary brush, a spring-motor for driving the brush in one direction, and a treadle for driving the 55 brush in the opposite direction and winding up the spring-motor, substantially as shown and described.

2. The combination, substantially as before set forth, of a rotary brush, a spring-motor 60 for driving the brush, a treadle for winding up the spring-motor, a hood over the brush, and a dust-receptacle.

In testimony whereof I affix my signature in presence of two witnesses.

SAMUEL L. BEAN.
